UNITED STATES PATENT OFFICE

ELIJAH WADE AND WILLIAM McAULAY, OF QUITMAN, GEORGIA.

IMPROVEMENT IN HORSE-POWERS.

Specification forming part of Letters Patent No. **223,197**, dated December 30, 1879; application filed October 21, 1879.

To all whom it may concern:

Be it known that we, **ELIJAH WADE** and **WILLIAM McAULAY**, of Quitman, in the county of Brooks and State of Georgia, have invented a new and Improved Horse-Power, of which the following is a specification.

Figure 1 is a plan of the device. Fig. 2 is a front elevation of the same.

Similar letters of reference indicate corresponding parts.

The object of this invention is to make more efficient the ordinary machine or mechanism in which the power of horses is exerted to drive other machinery.

The invention consists in a novel arrangement of a tongue and double-tree, in combination with the sweep or lever of a horse-power, whereby greater leverage may be obtained within a given circle.

In the drawings, A represents the frame of a building in which the horse-power is located. B is the king-post; C, the levers fixed in the king-post B and radiating therefrom.

D is a scantling or tongue, having one end inserted in a mortise in or otherwise fastened to the lever C and the other end fastened to the support E, which itself has one end fastened to the king-post B, while the other end serves as an axle for the wheel F.

G is a double-tree, secured on the scantling or tongue D for the attachment of the horses.

In an ordinary horse-power, intended, as is this one, especially for ginning cotton, the double-tree is attached to the lever C, as shown in dotted lines at H, Fig. 1, at a point, it will be seen, nearer the king-post B than is the point of attachment of the tongue or scantling D, to which is attached the double-tree G, for the scantling or tongue D is not used in the ordinary horse-power; hence the point of attachment H to the lever C is the most convenient, and is placed as far out toward the end of the said lever C as the side of the building will permit for the uninterrupted or free movement of the horses.

On a floor thirty-two feet square, which is the usual dimension of a ginning-room, the outer edge of the path traveled by the horses, hitched to the lever C in the usual manner, represents a circle of thirty feet in diameter, the said levers C being fifteen feet long from the center of the king-post B, and the point of the double-tree attachment being thirteen feet from the center of the king-post B.

In this improved arrangement the point of attachment to the lever C of the scantling or tongue D is fourteen and one-half feet from the center of the king-post B, and, as it is obvious to this point of attachment that the power is applied under the present arrangement, it will be seen that a gain of one and one-half foot more leverage is made on each lever C, so that within the limits of a circle of thirty feet in diameter as much effective power can be applied as within a circle of thirty-three feet in diameter by the old method, three feet of aggregate leverage being gained by this new arrangement over the greatest practicable leverage that can be had by placing the horses in front of the lever C, as shown at H.

As a substitute for the wheel F that supports the end of the support E, a brace may connect the outer end of the said support E with the king-post B.

Having thus described our invention, what we claim as new, and desire to secure by Letters Patent, is—

In horse-powers arranged in buildings A, the combination, with the sweep C, of the tongue D, provided with devices for attaching the horses, and the sustaining-bar E, the latter supported on wheel F at one end, and attached at the other to the king-post B, as shown and described.

ELIJAH WADE.
WILLIAM McAULAY.
